PRESSER-FOOT MECHANISM FOR SEWING-MACHINES.

1,287,891.

Specification of Letters Patent.

Patented Dec. 17, 1918.

Application filed May 23, 1916. Serial No. 99,285.

To all whom it may concern:

Be it known that we, HERBERT CORRAL and ALFRED LESLIE, subjects of the King of the United Kingdom of Great Britain and 5 Ireland, residing, respectively, at Parkview, Helensburgh, Dumbartonshire, Scotland, and Glasgow, Scotland, have invented certain new and useful Improvements in Presser-Foot Mechanisms for Sewing-Machines, of which the following is a specification, reference being had therein to the accompanying drawings.

This invention relates to presser-foot mechanism for sewing machines and more 15 particularly to presser-foot mechanism of the rearwardly vibrating type, wherein the presser-foot is mounted so as to be free to move with the feed-dog in the direction of feed and is returned to initial position by a 20 spring as the presser-foot is automatically lifted preparatory to the next feeding movement.

One of the objects of this invention is to provide a construction of vibrating presser- 25 foot mechanism which will avoid the drag on the work produced by similar devices heretofore used, while maintaining the presser-foot in fixed angular relation to the usual feed-dog. Another object of the in- 30 vention is to provide a vibrating presser-foot mechanism better adapted for running at high speed than constructions heretofore in use and comprising a minimum number of working parts.

To this end the presser-foot carrier, which is sustained by the lower end of the usual spring-pressed presser-bar, is mounted for translatory movement relatively to the presser-bar in a path which is upwardly 40 curved in the direction of feed; the purpose being to cause the downward thrust of the presser-bar to exert a force on the presser-foot carrier tending to move the latter in the direction of feed, without inclining the operative face of the presser-foot.

In the preferred embodiment of the invention the presser-foot is mounted upon a rearwardly movable presser-foot carrier, connected by two parallel links of equal 50 length to a laterally fixed carrier sustained by the usual spring-pressed presser-bar. The movable and fixed carriers have upwardly and rearwardly inclined opposed meeting

surfaces which are initially drawn into contact relation by a tension spring connected 55 at opposite ends to the respective carriers. In the initial position of the parts the parallel links are vertically disposed, so that the downward thrust of the presser-bar exerts no rearward thrust on the movable presser- 60 foot carrier, that is to say, the presser-foot may be considered as locked against rearward movement due to the downward pressure of the presser-bar spring. An initial displacement of the movable carrier in the 65 direction of feed, however, will cause the downward thrust of the presser-bar to exert a rearward thrust on the movable carrier, which will increase with the displacement. This increasing rearward thrust is very desirable in overcoming the constantly increasing reaction of the usual return spring. On account of the parallel connection the motion of the presser-foot is strictly translatory; angular turning movements thereof being 70 75 eliminated.

In the accompanying drawings forming a part of this specification, the figure represents an end elevation of a sewing machine head showing the usual needle and presser-bars and the improved presser-foot mechanism sustained in operative relation therewith.

In the preferred embodiment of the invention, as illustrated, the usual sewing machine head 1 is provided with bearings for the needle-bar 2 to which is secured the lateral stud 3 embraced by one end of a pitman 4, the other end of which embraces the crank-pin 5 on the crank-disk 6 carried as 80 usual by the main-shaft. The presser-bar 7 journaled in parallel relation to the needle-bar, carries a collar 8, between which and the frame the usual compression spring 9 is located. Any of the usual types of automatically operated presser-bar lifting devices may be employed to lift the presser- 85 90 95 foot during the return stroke of the feed-dog. For example a cam 12 on the crank-disk 6 may be provided to lift a slide-bar 13 carrying a lateral arm 14 arranged to engage under a clutch-collar 15 surrounding the presser-bar in a manner well-known. The cam 12 is so situated that it will lift the presser-bar while the needle is in the work, 100 105 at which time the usual feed-dog is execut-

ing its return movement below the throat-plate.

The presser-foot 16 is secured by a screw 17 to a pin 18 projecting downwardly from 5 the movable presser-foot carrier 19 in which are mounted the transverse pins 20 embraced by the lower ends of a pair of parallel links 21 of equal length, the upper ends of which embrace transverse pins 22 sustained by the 10 laterally fixed carrier 23 mounted on the presser-bar 7. The carriers 19 and 23 have opposed, upwardly and rearwardly inclined meeting surfaces 19' and 23' respectively, initially held in contacting relation by a 15 spring 24, in which position the links 21 are disposed at right angles to the direction of feed. It will be noted that the movable carrier 19 will remain parallel to the fixed carrier 23 in any of the positions it may assume and it will be further noted that the 20 presser-foot 16 will move in an upwardly inclined path along the arc of a circle, relatively to the fixed carrier 23, the upward inclination of the path increasing with the 25 rearward displacement of the movable carrier. The links 21 may therefore be considered as guiding means which determine the path of translatory movement of the carrier 19 relative to the carrier 23 and hence to 30 the presser-bar 7.

In the operation of the device, when the usual feed-dog 25 moves into contact with the work, as shown on the drawing, its initial movement in the direction of feed will 35 displace the lower ends of the links 21 rearwardly, thus permitting the downward thrust of the presser-bar spring 9 to exert a constantly increasing rearwardly directed force upon the movable carrier which will 40 balance or overcome the constantly increasing reaction of the spring 24 as well as the inertia of the moving parts and the slight friction at the ends of the links 21. The work engaging face of the presser-foot will 45 also remain constantly in fixed angular relation to the presser-bar and therefore in parallelism with the feed-dog, with the result that the work will be uniformly compressed throughout the feeding stroke.

Having thus set forth the nature of the invention, what we claim herein is:—

1. In a sewing machine, the combination with a spring-pressed presser-bar, automatic lifting means therefor, a feed-dog, a presser-foot opposed to said feed-dog, and pivotally supported on said presser-bar, the path of movement of said foot being in a plane parallel to the feed-dog during the work-feeding operation, whereby the movement of the 55 presser-bar assists the feed-dog in advancing the work.

2. In a sewing machine, in combination, a feed-dog, a spring-pressed presser-bar, automatic lifting means therefor, a presser-foot, a pivotal mounting for said presser- 60

foot carried by said presser-bar and guiding, supporting, and sustaining the presser-foot movably in an upwardly inclined path relatively to the presser-bar, and with its operative face in fixed angular relation with 70 said presser-bar.

3. In a sewing machine, the combination with a presser-bar, a spring for depressing and automatic means for lifting the same, a work-support, a feed-dog, a presser-foot carried by the said bar, said presser-foot being supported upon the presser-bar for movement rearwardly in a plane parallel to the work-support, locking means for the presser-foot acting to hold the latter against rearward movement under the action of the presser-bar spring until released by the rearward feed of the fabric under the action of the feed-dog, and means for restoring the presser-foot to its forward position. 75 80

4. In a sewing machine, in combination, a presser-bar, a spring for depressing and means for lifting the same, a presser-foot, devices for mounting the latter upon said presser-bar for rearward movement in a 90 plane at right angles to the presser-bar, means for restoring said presser-foot to initial position upon release of pressure, the devices for mounting the presser-foot upon the presser-bar comprising means for transmitting the pressure of the spring to the presser-foot to produce rearward movement of the latter, said means being adapted to act only after an initial rearward movement 95 of the foot. 100

5. In a sewing machine, in combination, a presser-bar, a spring for depressing and means for lifting the same, a presser-foot mounted on said presser-bar for rearward movement along a path curved upwardly relatively to said presser-bar, whereby the pressure of said spring will tend to displace the presser-foot rearwardly with a force increasing proportionately to the rearward movement of the foot, and resilient restoring means for said foot, said displacing and restoring means substantially balancing one another to avoid slipping of the presser-foot relative to the work. 105 110

6. In a sewing machine, the combination with a spring-pressed presser-bar and lifting means therefor, of spaced parallel links carried by said presser-bar, a presser-foot sustained by said links, means for determining the initial position of said presser-foot relative to said presser-bar, and a spring for yieldingly holding said presser-foot in initial position. 115 120

7. In a sewing machine, the combination with a feed-dog, a spring-pressed presser-bar and lifting means therefor, of spaced parallel links carried by said presser-bar, a presser-foot sustained by said links, means for determining the initial position of said 125 130

presser-foot relative to said presser-bar, said links being disposed substantially at right angles to the direction of feed when the presser-foot is in initial position, and a spring for returning said presser-foot to initial position after a feeding movement.

In testimony whereof we have signed our

names to this specification, in the presence of two subscribing witnesses.

HERBERT CORRAL.
ALFRED LESLIE.
